(57) **ABSTRACT**

There is disclosed apparel for providing protection and illumination. In an embodiment, a gaiter has a top portion and a bottom portion with a layer of material extending therebetween. The layer of material provides a protective covering to a lower limb of the user. At least one securement mechanism provides an adjustable attachment of the gaiter to the user. The selective mechanism allows attachment of the gaiter with a variety of footwear. A light housing is integrally disposed on an outward portion of the layer of material of the gaiter. The light housing provides illumination adjacent to the foot of a user. The combination of the gaiter and the light housing together provide a body-worn lighting device without attaching the light housing directly to any of the user, the footwear worn by the user, and clothing worn by the user. Other embodiments are disclosed.

LIGHTED GAITERS

REFERENCE TO PENDING PRIOR PATENT APPLICATION

This application claims the benefit under 35 U.S.C. 119(e) of U.S. Provisional Patent Application No. 63/148,140, filed Feb. 11, 2021, by John Ng, et al., for "LIGHTED GAITERS," which patent application is hereby incorporated herein by reference.

BACKGROUND

Generally, traditional gaiters only function to insulate the lower limb. Being easily removable and usable with a wide variety of clothing and footwear, gaiters may provide supplement warmth and protection from weather and other outdoor hazards when desired.

SUMMARY

This Summary is provided to introduce a selection of concepts in a simplified form that are further described below in the Detailed Description. This Summary is not intended to identify key aspects or essential aspects of the claimed subject matter. Moreover, this Summary is not intended for use as an aid in determining the scope of the claimed subject matter.

In an embodiment, there is provided apparel for providing protection and illumination adjacent to a foot of a user. The apparel may include a gaiter having a top portion and a bottom portion in opposition to one other, a layer of material extending between the top portion and the bottom portion, the layer of material extending a given distance to provide a protective covering to a lower limb of the user, and at least one securement mechanism to provide an adjustable attachment of the gaiter to the lower limb of the user. The selective mechanism may allow attachment of the gaiter to the lower limb of the user with a variety of footwear. A light housing may be integrally disposed on an outward portion of the layer of material of the gaiter. The light housing may be configured to provide illumination adjacent to the foot of a user. The combination of the gaiter and the light housing together may provide a body-worn lighting device positionable between the foot and the knee of the user without attaching the light housing directly to any of the user, the footwear worn by the user, and clothing worn by the user.

In another embodiment, there is provided a gaiter having a top portion and a bottom portion in opposition to one other, a layer of material extending between the top portion and the bottom portion, the layer of material extending a given distance to cover a knee, a shin, a calf, an ankle, and a part of the footwear of the user. A light housing may be integrally disposed on an outward portion of the layer of material of the gaiter.

Other embodiments are also disclosed.

Additional objects, advantages and novel features of the technology will be set forth in part in the description which follows, and in part will become more apparent to those skilled in the art upon examination of the following, or may be learned from practice of the technology.

BRIEF DESCRIPTION OF THE DRAWINGS

Non-limiting and non-exhaustive embodiments of the present invention, including the preferred embodiment, are described with reference to the following figures, wherein

2

like reference numerals refer to like parts throughout the various views unless otherwise specified. Illustrative embodiments of the invention are illustrated in the drawings, in which:

5 FIG. 1 illustrates a front perspective view of one lighted gaiter with a light housing positioned in the front upper portion;

10 FIG. 2 illustrates a perspective view of the one lighted gaiter of FIG. 1 with the light housing positioned in the upper front portion;

FIG. 3 illustrates a perspective view of one lighted gaiter with a light housing positioned in the upper lateral portion and one light housing positioned in the lower lateral portion;

15 FIG. 4 illustrates a perspective view of one lighted gaiter with multiple lights embedded in the upper front, lower front, upper lateral, and lower lateral portions of the gaiter;

20 FIG. 5 illustrates a perspective view of one lighted gaiter with multiple lights embedded in the upper front, lower front, and lower lateral portions of the gaiter and a battery compartment located in the upper lateral portion of the gaiter;

FIG. 6 illustrates a perspective view of one multiple layered lighted gaiter with a light housing positioned in the upper front portion of the outer layer of the gaiter;

25 FIG. 7 illustrates a perspective view of a light housing molded directly onto the surface of the upper front portion of the gaiter;

FIG. 8 illustrates a perspective view of a holster molded directly onto the surface of the upper front portion of the gaiter and a light housing that can be attached thereto;

FIG. 9 illustrates a perspective view of a light housing, a backing plate, and openings in the upper front portion of a gaiter;

30 FIGS. 10 and 11 illustrate a perspective view of a pair of gaiters with a crown sized to retain a light housing therein.

DETAILED DESCRIPTION

Embodiments are described more fully below in sufficient detail to enable those skilled in the art to practice the system and method. However, embodiments may be implemented in many different forms and should not be construed as being limited to the embodiments set forth herein. The following detailed description is, therefore, not to be taken in a limiting sense.

45 In various embodiments, there are provided lighted gaiters that illuminate obstacles for the user or aid visibility of the user to others, or a combination of the two. Furthermore, the lighted gaiters provide insulation and protection for the lower limb.

50 Lighted gaiters may generally be useful to outdoor enthusiasts such as hunters, hikers, and fishermen. Lighted gaiters may also be used by workers in low light work environments and conditions.

55 With reference to FIGS. 1 and 2, and in an embodiment, there is shown one lighted gaiter 10 with a light housing 10. The light housing 10 may be positioned in the front upper portion of gaiter 10. Gaiter 10 is shown disposed on a shoe 30 in FIG. 2.

60 Unlike traditional gaiters, lighted gaiters 10 not only provide an added physical layer that provides insulation for the lower limb against different climate conditions such as rain, snow, wind, and sun, but each of gaiters 10 also provides lighting for the user or wearer. This may aid the wearer in visualizing obstacles and objects in low light conditions or in complete darkness while allowing the wearer's hands to be free of carrying any illuminating

devices such as a flashlight. The lighting from the lighted gaiters **10** provides more superior ground level illumination without the need for crouching in order to create more desired ground level lighting from other illuminating devices, such as, for example, a headlamp. As compared to using a headlamp, lighted gaiters **10** may likewise provide hands free illuminations; nonetheless, lighted gaiters provide a light source that is away from the wearer's nose and mouth, which helps prevent impaired illumination from exhalation fogging in frigid weather conditions.

Now referring to FIG. 3, and in one embodiment, there is shown one lighted gaiter **10** with light housing **20** positioned in an upper lateral portion and another light housing **10** positioned in the lower lateral portion. Furthermore, gaiter **10** is disposed on footwear **30** (which may be referred to as a boot **30** or a shoe **30**). Furthermore, it should be appreciated that unlike a specialized shoe or pant-leg carrying a light device, Lighted gaiter **10** may be worn over any footwear or boot. Furthermore, lighted gaiter **10** may be donned or doffed very quickly. Being coupled together with one another, lighted gaiter **10** quickly positions light housing **20** with preselected adjustment of securement features. Additionally, light housing **20** is protected and less likely to get misplaced as being an integral portion of lighted gaiter **10**.

With reference now to FIG. 4, and in another embodiment, there is shown one lighted gaiter **10** with multiple lights **20** embedded in upper front, lower front, upper lateral, and lower lateral portions of gaiter **10**. Boot **30** is shown beneath gaiter **10**.

With reference now to FIG. 5, and in an embodiment, there is shown one lighted gaiter **10** with multiple lights embedded in upper front, lower front, and lower lateral portions of gaiter **10**. A battery compartment **40** may be located in the upper lateral portion of gaiter **10**. Boot **30** is shown beneath gaiter **10**.

With reference now to FIG. 6, and in one embodiment, there is shown one multiple layered lighted gaiter **10** (with an inner layer **10A** and an outer layer **10B**). Light housing **20** may be positioned in an upper front portion of the outer layer **10B** of gaiter **10**.

Looking at FIG. 7, and in an embodiment, there is shown light housing **20** molded directly onto the surface of the upper front portion of gaiter **10**. In this configuration, light housing **20** is a permanent, integral portion of gaiter **10**.

Looking now at FIG. 8, an in another embodiment, there is shown a holster **50** molded directly onto the surface of an upper front portion of gaiter **10**. Light housing **20** may be selectively attached to the holster **50**. In this configuration, light housing **20** is removable from gaiter, and light housing **20** together with holster **50** forms an integral portion of gaiter **10**.

With reference now to FIG. 9, and in an embodiment, light housing **20** may be removably attached to gaiter **10**. A backing plate **60** may be configured within an interior surface of gaiter **20**. Openings **70** may be formed through gaiter **10**. Extensions **80** from light housing **20** may be configured to extend through openings **70** and selectively attach with backing plate **60** to position light housing **20** on the outer surface of gaiter **10**. Light housing **20** using backing plate **60** forms a removable and integral portion of gaiter **10**.

With reference now to FIGS. 10 and 11, and in an embodiment, there is shown a pair of multiple layered lighted gaiters **10** (with an inner layer **10A** and an outer layer **10B**). Light housing **20** may be positioned in an upper front portion of the outer layer **10B** of gaiter **10**. Outer layer **10B**

may include a crown **90** formed by a circular rubber insert sewn onto sleeve of the leg gaiter. Crown **90** may be configured to retain light housing **20** in place with a compression fit. The sleeve may provide a fabric layer sewn on the top upper portion of the leg gaiter that holds crown **90**. The shape of the sleeve may be provided in various forms. The crown can also be in different shapes and made with different materials other than rubber and plastic. The light housing (as discussed herein) can be made in different shapes, sizes, and dimensions.

Lighted gaiters not only offer protection to the lower limb but may also provide lighting that allows the wearer to see and identify obstacles on and off the ground, in low light conditions and in complete darkness, while allowing the wearer hands to be free from carrying any illuminating devices such as a flashlight.

The light on the lighted gaiters also is superior to traditional gaiters by aiding visibility of the wearer to others who are around the wearer, such visibility provides safety to the wearer and aids in accident prevention in the dark.

The lighting also provides more superior ground level illumination as compared to using a flashlight or a headlamp as superior ground level illumination eliminates the need for crouching the user's body to redirect light source in order to achieve increased ground level visibility. As compared to using a headlamp, lighted gaiters provide light source away from the wearer's nose and mouth, which helps prevent impaired illumination from exhalation fogging in frigid weather conditions.

One or more lighted gaiter may be superior to the use of flashlights as the lighted gaiters provide illumination for the wearer while freeing the one's hands for other tasks.

In general, various embodiments of lighted gaiters create a layer of insulation to the lower limb while providing lighting that allows the wearer to see and identify obstacles on and off the ground in low light conditions and in complete darkness. The light on the gaiters can also aid visibility of the wearer to others who are around the wearer. Such visibility provides safety to the wearer and aids in accident prevention in the dark. A wearer can achieve hands free illumination, superior ground level lighting, and obstruction free lighting from exhalation fogging as discussed.

The lighted gaiters are designed to add one or more layers to the lower limb that cover the knee, shin, calf, ankle, and part of the foot. The texture of the lighted gaiters may be either soft or hard, or a combination of the two, with prior texture form that offers flexibility and durability and latter texture form that can withstand external blunt forces such as one from a snake bite without permitting perforation.

The physical layer added by the gaiters also provide insulation for the wearer against different climate conditions such as rain, snow, wind, and sun. Various materials may be used in or added to the composition of the gaiters and give rise to various textile properties such as semi-permeability that allows the flow of air and moisture through the material and water resistance or waterproof properties.

The gaiter may be wrapped around the lower limb and secured by mechanism of buttons, Velcro, hooks, zipper, clasps, or by a combination of the mechanisms. The gaiters may contain one or more elastic bands within the layer of the gaiter that serves to secure the gaiter around the top and bottom portions of the lower limb. The gaiter may include a crown formed by a circular rubber insert sewn onto a sleeve of the leg gaiter. This crown may be configured to retain the light housing in place with a compression fit. The sleeve may provide a fabric layer sewn on the top upper portion of the leg gaiter that holds the crown. The shape of the sleeve may

5

be provided in various forms. The crown can also be in different shapes and made with different materials other than rubber and plastic. The light housing (as discussed herein) can be made in different shapes, sizes, and dimensions.

The gaiter may include a strap that secures the gaiter around the bottom of the shoe by mechanism of buttons, Velcro, hooks, zipper, clasps, or by a combination of the mechanisms on the strap.

The lighted gaiters provide illumination for the wearer using one or more light emitting diodes (LEDs) disposed in a water resistant or waterproof light housing. The light emitting diodes (LEDs) may be positioned on the surface of or embedded within the layer of the gaiter operatively connected to a waterproof battery container. The LEDs may be positioned in the top, middle, or lower portion in the front, lateral, or back side of the gaiter, or in combination of the portions and sides.

The LEDs may be disposed to shine forward and downward ahead of the toe of the footwear or to shine downward on the lateral or back side of the lower limb, or from a combination of the positions. The side LEDs may emit light of one or more frequencies, colors, or intensities. The frequencies, colors, and intensities of the LEDs may be controlled by an electronic circuit board or a printed circuit board operatively coupled to the LEDs. The waterproof light housing and the waterproof battery container comprise a battery compartment with one or more batteries therein operatively coupled to the light to power the light and a switch operatively coupled to the battery and the light to control operation of the electronic circuit board or printed circuit board and the light.

In various embodiments, the waterproof light housing may be directly molded to the surface of the gaiter. The waterproof light housing may be attached to a designated holster that is directly molded to the surface of the gaiter. The waterproof light housing may be secured to the surface of the gaiter by coupling a backing plate with the posterior or lateral side of the light housing through purposeful openings in the gaiter.

Although the above embodiments have been described in language that is specific to certain structures, elements, compositions, and methodological steps, it is to be understood that the technology defined in the appended claims is not necessarily limited to the specific structures, elements, compositions and/or steps described. Rather, the specific aspects and steps are described as forms of implementing the claimed technology. Since many embodiments of the technology can be practiced without departing from the spirit and scope of the invention, the invention resides in the claims hereinafter appended.

What is claimed is:

1. Apparel for providing protection and illumination adjacent to a foot of a user, the apparel comprising:
a gaiter having a top portion and a bottom portion in opposition to one another, a layer of material extending between the top portion and the bottom portion, the layer of material extending a given distance configured to provide a protective covering to a lower limb of the user, a flap formed by an outer fabric layer disposed on an outermost surface of the layer of material, and at least one securing fastener to provide an adjustable attachment of the gaiter to the lower limb of the user, wherein the at least one securing fastener is configured to allow attachment of the gaiter to the lower limb of the user with a variety of footwear;
a light housing positioned in the flap in direct contact against each of the layer of material and the outer fabric

6

layer, the light housing positioned to extend through the outer fabric layer of material of the gaiter, the light housing includes at least one light emitting diode (LED), and the at least one light emitting diode (LED) having a configuration to shine forward and downward ahead of a toe of the footwear worn by a user, and the light housing configured to provide illumination adjacent to a foot of a user; and

the combination of the gaiter and the light housing together providing a body-worn lighting device positionable between the foot and a knee of the user without attaching the light housing directly to any portion of the user, the footwear worn by the user, and clothing worn by the user.

2. Apparel in accordance with claim 1, wherein the gaiter is configured to cover the knee, a shin, a calf, an ankle, and a part of the footwear of the user.

3. Apparel in accordance with claim 1, wherein the gaiter is configured to cover a part of a shin, a part of a calf, an ankle, and a part of the footwear of the user.

4. Apparel in accordance with claim 1, wherein the protective covering of the layer of material is configured to shield the knee, a shin, a calf, an ankle, and a part of the footwear of the user from external forces.

5. Apparel in accordance with claim 1, wherein the protective covering of the layer of material is configured to shield a part of a shin, a part of a calf, an ankle, and a part of the footwear of the user from external forces.

6. Apparel in accordance with claim 1, wherein the protective covering of the layer of material is configured to provide insulation from climate conditions to a part of a shin, a part of a calf, an ankle, and a part of the footwear of the user from external forces.

7. Apparel in accordance with claim 1, wherein the at least one securing fastener further includes at least one of buttons, hook-and-loop fasteners, hooks, a zipper, and clasps.

8. Apparel in accordance with claim 1, wherein the at least one securing fastener includes one or more elastic bands located within the layer of material of the gaiter so as to selectively secure the top portion and the bottom portion of the gaiter around the lower limb.

9. Apparel in accordance with claim 1, wherein the light housing is operatively connected to a waterproof battery container carried by the gaiter.

10. Apparel in accordance with claim 1, wherein the light housing is disposed in a waterproof light housing integrally molded on the outward portion of the layer of material of the gaiter.

11. Apparel in accordance with claim 1, further comprising a crown formed by a circular rubber insert sewn onto the layer of material of the gaiter, and wherein the light housing is integrally retained by the crown into the layer of material of the gaiter.

12. Apparel in accordance with claim 1, wherein the light housing is positioned adjacent to the top portion of the gaiter.

13. Apparel in accordance with claim 12, wherein the light housing is positioned in a front portion of the gaiter.

14. Apparel in accordance with claim 1, wherein the gaiter includes a crown formed by a circular rubber insert sewn on a sleeve of the gaiter, and the crown is configured to retain the light housing in place with a compression fit.

15. Apparel in accordance with claim 1, wherein the protective container sleeve defines an opening for insertion and removal of the light housing.

16. A gaiter comprising: a top portion and a bottom portion in opposition to one another, a layer of material extending between the top portion and the bottom portion, the layer of material extending a given distance (1) configured to cover a knee, a shin, a calf, and an ankle, the layer of material extending the given distance (2) further configured to cover a part of footwear of a user, a flap formed by an outer fabric layer disposed on an outermost surface of the layer of material, and a light housing positioned in the flap in direct contact against each of the layer of material and the outer fabric layer, the light housing positioned to extend through the outer fabric layer of the gaiter, the light housing includes at least one light emitting diode (LED), and the at least one light emitting diode (LED) having a configuration to shine forward and downward ahead of a toe of the footwear worn by the user, and the light housing configured to provide illumination adjacent to a foot of the user.

17. The gaiter of claim **16**, wherein the layer of material is configured to be positionable between the foot and the knee of the user without attaching the light housing directly to any portion of the user, the footwear worn by the user, and clothing worn by the user.

18. The gaiter of claim **16**, wherein the protective container sleeve defines an opening for insertion and removal of the light housing.
